CLAIM

The ornamental design for a gift box with window, as shown and described.

DESCRIPTION

FIG. 1 is a perspective view of a gift box with window showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view thereof, showing in an exploded position;

FIG. 9 is a perspective view of the outer box portion, shown separately to show aspects of the design that are not visibly when combined;

FIG. 10 is a perspective view of the inner box portion in an unfolded position; and,

FIG. 11 is a top view thereof.

1 Claim, 10 Drawing Sheets
